CONVERTIBLE BED TABLE

George Klotz, New York, N. Y., assignor to
 H. & G. Klotz, a partnership composed of
 Henri Klotz and George Klotz

Application February 4, 1929, Serial No. 337,257,
 and in France February 3, 1928

11 Claims. (Cl. 45—11)

This invention relates to convertible bed tables. It is an object of my invention to provide a convertible table, of a sort which may be used by a person in bed; said table being adapted to be used 5 either in a horizontal position, to hold dishes, or in an inclined position, to hold a book for reading, or as a writing desk, etc.

Another object is to provide means whereby my 10 table may be interchangeably used as described above.

Other objects will appear as the description 15 proceeds.

My invention will best be understood by referring 20 to the following description, taken in conjunction with the accompanying drawings, in which like reference characters denote like elements throughout, and in which:

Fig. 1 is a bottom plan view of the table;

Fig. 2 is a side elevation of the table when being 25 used flat;

Fig. 3 is a side elevation of the table being used as a writing desk;

Fig. 4 is an enlarged detail view of the locking 30 mechanism for the feet, to be used when the table is flat;

Fig. 5 is an enlarged bottom plan view, partly 35 in section, of the locking mechanism for the feet when folded;

Fig. 6 shows a longitudinal section of one of 40 the extensible legs permitting the use of the table as a writing desk;

Fig. 7 is a section on line A—A of Fig. 1, showing 45 the ledge in position to hold a book or other object;

Fig. 8 is a section on line A—A of Fig. 1, showing 50 the ledge in position adapted to be used as a writing desk;

Fig. 9 is a similar view showing the ledge in its 55 inoperative position.

According to the embodiment of my invention 60 shown in the drawings, the table 1, which may be preferably of wood, in order that it might be light, is of generally rectangular shape, being of greater width than length, and is supplied on its under side with two groups of legs. The first group 65 comprises four legs 2, of equal length, being preferably of wood and located one at each of the four corners. The second group comprises two legs 3 placed at the two corners on one long side. The legs 2 and 3 are all hinged at 4 permitting them 70 to be folded inwardly against the bottom of the table.

On the longitudinal side opposite legs 3, the 75 table 1 has an indentation or cut-away portion forming thus two prolongations 5—5. These pro-

longations serve first, as arm rests when the table is horizontal, the four legs 2 being opened and legs 3 folded, as is represented in Fig. 2; and serve secondly, as legs when the table is used as a writing desk, the two legs 3 opened and legs 2 folded, 60 as shown in Fig. 3.

In order to give the table a variable inclination when it is used as a writing desk, the legs 3 are 65 extensible. To this end, they are formed, as shown in Fig. 6, of two telescopic tubes 3a and 3b of wood or metal of rectangular, round or other convenient cross section. A locking mechanism comprising a spur or pin 6, fixed within the interior of tube 3b by means of a spring 7, which tends to push it externally thru a hole in the wall 70 of tube 3b, permits the immobilization of the two tubes, to produce any given length, by entering into one of the spaced holes 8, pierced in external tube 3a.

The four legs 2, of fixed length, as well as the 75 two extensible legs 3, are provided with a mechanism for locking them in the folded position. As shown in Fig. 5, the locking of each leg in the folded position is secured by means of a pin 9, mounted on a flat spring 10, lodged in a cavity 11 in a 80 block of wood 12 (Figs. 1 and 5); the said cavity 11 being closed laterally by a metal plate 13, which is pierced with a hole permitting the pin to extend outwardly. This pin is adapted to lodge in a cavity formed by a spherical metal cap 85 mounted in a plate 14 on the adjacent side of leg 2, or in tube 3a of leg 3.

In Fig. 4 is represented one form of means for 90 immobilizing legs 2 in the open position; the same mechanism being shown on a slightly smaller scale in Figs. 1, 2 and 3. As shown, an arm 15 is pivotally mounted at 16 on the side of the leg. This arm bears a longitudinal slot 17 in which slides a pin 18, carried on an angle iron 19, fixed 95 on the bottom of the table. A spring 20, fixed on the arm and bearing against pin 18, pushes the latter against the upper edge 21 of the groove 17. This edge has, at its extremity farthest from the leg a notch 22 in which, under the action of spring 20, pin 18 lodges when the leg is opened, 100 thus locking the leg in open position.

The table is provided with a ledge disposed at 105 the edge of the indentation and projecting above the upper face of the table in a manner to maintain upon the table, when used as a writing desk, an object such as a book, writing paper, etc.

As shown in Figs. 1, 7, 8, and 9, this ledge comprises an L-shaped piece 23, preferably of metal, 110 fixed by two flat springs 24 and 25 to a rod 26, which slides in grooves 27 and 28 formed in cleats

29 and 30. These cleats may be made as long as the table in order to reinforce it, as well as to serve as guides for bar 26.

Ledge 23 bears on its interior a projection 31 of 5 a sort that the ledge can occupy three different positions to be indicated later; the projection can be made flush with the table (Fig. 7); the ledge then has a height corresponding to the lateral face of element 23, and can be used to hold a book, for 10 example. In Fig. 8, projection 31 rests upon the bottom of the table, and the height of the ledge is diminished with respect to Fig. 7 by its thickness. The ledge is then in a suitable position for writing, etc. Finally, in Fig. 9, the ledge is 15 moved completely out of the way.

These three positions are possible due to the elasticity of the flat springs 24 and 25, and the sliding of bar 26 in grooves 27 and 28. Clips 32 and 33, rotatable about the same axis 34, are metallic plates and serve to immobilize or in other 20 words hold the ledge in the three indicated positions. Of course, these clips could be replaced by any desired mechanism; in the same manner the ledge might be merely a projection, without the 25 extra projection or step 31.

In order to hold the object supported by the ledge, especially in the case of a book, one or preferably two bands 35 (Figs. 1 and 7) pass thru slots 36 and 37 cut into ledge 23 and projection 31, pass across the table and may be made to pass, for example, over the first and the last page of the book, which is in this manner held perfectly, while permitting the reading of all the 30 pages.

35 While I have, in describing an embodiment of my invention, shown and described certain details of construction, it is to be understood that these are not to be considered as limiting, but are illustrative only. My invention is to be considered limited only by the prior state of the art 40 and the scope of the appended claims.

I claim:

1. In combination, a table, a ledge adapted to 45 project above the upper surface of said table at the lower edge thereof, means for mounting said ledge in sliding relation to said table, comprising a pair of cleats, extending along, and serving to strengthen said table, grooves in said 50 cleats, a crossbar sliding in said grooves, spring arms spaced apart and connected with said crossbar, said spring arms being connected at their extremity with said ledge, and means for holding said ledge in a desired position.

2. In combination, a bed table top, means for 55 supporting said table top in a horizontal position, means for supporting said table top in an inclined position including extensible legs adjacent one edge of said table top for changing the degree of inclination of the table top, hinge 60 means for permitting said legs to assume any desired acute angle relative to the plane of the top of the table, and a pair of prolongations on said table top on an opposite edge thereof, said prolongations being spaced to form an indented portion adapted to fit about the body of the user and being of a length sufficient to permit the same to function as legs.

3. In combination, a table top, means attached 70 to said table top for supporting said table top in an inclined position, a ledge resiliently mounted on said table top and in sliding relationship therewith, said ledge adapted to project to a full extent above the upper surface of said table top at the lower edge thereof, means for restraining 75 said ledge from projecting to said full extent

while permitting it to project to an appreciable extent, and means for completely preventing said ledge from projecting above the upper surface of said table top.

4. The combination comprising a table top, a ledge, resilient means slidably mounted underneath said table top for supporting said ledge in sliding relationship with respect to said table top, said means adapted to permit said ledge to be shifted between a position underneath said table top and a position of full projection above the upper surface of said table top at one edge thereof, and means on said ledge for holding said ledge in a position of partial projection above the upper surface of said table top.

5. The combination comprising a table top, a ledge, resilient means slidably mounted underneath said table top for supporting said ledge in sliding relationship with respect to said table top, said means adapted to permit said ledge to be shifted between a position underneath said table top and a position of full projection above the upper surface of said table top at one edge thereof, and means on said ledge for holding said ledge in a position of partial projection above the upper surface of said table top, said last mentioned means comprising a longitudinal projection on said ledge, said projection having an upper surface substantially flush with the upper surface of said table top and forming an extension thereof when said ledge is in a position of full projection, and resting against the under surface of said table top when said ledge is in a position of partial projection.

6. The combination comprising a table top, a ledge, resilient means slidably mounted underneath said table top for supporting said ledge in sliding relationship with respect to said table top, said means adapted to permit said ledge to be shifted between a position underneath said table top and a position of full projection above the upper surface of said table top at one edge thereof, means on said ledge for holding said ledge in a position of partial projection above the upper surface of said table top, and means attached directly to said table top for supporting said table top in a horizontal and in an inclined position.

7. In combination, a table top, means for supporting said table top in a plurality of inclined 125 positions, said means comprising a plurality of extensible legs hinged adjacent one edge of said table top and adapted to assume any desired acute angle relative to the table top, a pair of prolongations on each table top on an opposite 130 edge thereof, said prolongations being spaced to form an indented portion adapted to fit about the body of the user and being of a length sufficient to permit the same to function as legs, and means on said hinged legs for holding the 135 same in a plurality of extensible positions.

8. In combination, a table top, means for supporting said table top in a plurality of inclined positions, said means comprising a plurality of extensible legs hinged adjacent one edge of said 140 table top and adapted to assume any desired acute angle relative to the table top, means on said legs for holding the same in a plurality of extensible positions, spaced prolongations at the opposite edge of the table top forming an indented portion therebetween adapted to fit about the front part of the body of the user, and an adjustable ledge adapted to fit over the edge of said indented portion, said ledge extending 145 transversely of said table top.

9. In combination, a table top, means for supporting said table top in a plurality of inclined positions, said means comprising a plurality of extensible legs hinged adjacent one edge of said table top and adapted to assume any desired acute angle relative to the table top, means on said legs for holding the same in a plurality of extensible positions, spaced prolongations at the opposite edge of the table top forming an indented portion therebetween adapted to fit about the front part of the body of the user, an adjustable ledge adapted to fit over the edge of said indented portion, said ledge extending transversely of said table top, slots in said ledge, flexible bands about said table top, one band passing through each slot, said bands adapted to hold objects on said table top and to permit said ledge to be adjusted without removal of said bands. 10. In combination, a table top, a plurality of legs hinged adjacent one edge of said table top and adapted to assume any desired acute angle relative to the table top, spaced prolongations at the opposite edge of the table top forming an indented portion therebetween adapted to fit about the body of the user and to support the table top free from the body of the user, and a ledge adapted to fit over the edge of said indented portion, said ledge extending transversely of said table top, slots in said ledge, flexible bands about said table top, one band passing through each slot, said bands adapted to hold objects on said table top and to permit said ledge to be adjusted without removal of said bands. 11. In combination, a table top, means for supporting said table top in a plurality of inclined positions, said means comprising adjustable leg means for supporting said table top at one edge thereof, a pair of prolongations on said table top on an opposite edge thereof, said prolongations being spaced to form an indented portion adapted to fit about the body of the user and being of a length sufficient to permit the same to function as legs, and a ledge adapted to fit over the edge of said indented portion, said ledge extending transversely of said table top.
